UNITED STATES PATENT OFFICE.

GEORGE W. SHIEBLER, OF BROOKLYN, NEW YORK.

DESIGN FOR A BACK FOR BRUSHES, &c.

SPECIFICATION forming part of Design No. 23,331, dated June 5, 1894.

Application filed February 16, 1894. Serial No. 500,424. Term of patent 3½ years.

To all whom it may concern:

Be it known that I, GEORGE W. SHIEBLER, a citizen of the United States, residing at Brooklyn, in the county of Kings and State 5 of New York, have invented a new and original Design for the Back of a Brush or other Toilet Article, of which the following is a specification, reference being had to the accompanying drawings, in which I have represented my design by a plan view Figure 1. 10 and cross section Fig. 2. at the line y. y. of Fig. 1.

The leading feature of my design consists in the design of the raised leaflet and graduated pearl ornaments. The pattern comprises the principal raised ornaments at one 15 end having the acanthus leaf d and scrolls e e, the gadroon scrolls f f' at opposite sides,

and the pearl ornaments h. The graduated pearl ornaments i i' and curved ribs l l' extend out from the ornaments, and the gadroon scroll and leaf ornaments o o' o' are on and adjacent to the corners c c' and extend out from the graduated pearl ornaments i i' and across near the end. The surface portions a and b are plain.

What I claim is--

The design for the back of a brush or other toilet article, substantially as shown and described.

Signed by me this 13th day of February, 1894.

GEO. W. SHIEBLER.

Witnesses:

RICHARD F. COLE,
ALBERT WHITE.
